Primary Examiner — Janice Hallmark*Assistant Examiner* — Omeed Agilee(74) *Attorney, Agent, or Firm* — Birch, Stewart, Kolasch & Birch, LLP(57) **CLAIM**

The design for an ultrasound probe, as shown and described.

DESCRIPTION

FIG. 1 is a perspective view of an ultrasound probe according to a first embodiment;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a perspective view of an ultrasound probe according to a second embodiment;

FIG. 9 is a front view thereof;

FIG. 10 is a back view thereof;

FIG. 11 is a top view thereof;

FIG. 12 is a bottom view thereof;

FIG. 13 is a right side view thereof; and,

FIG. 14 is a left side view thereof.

1 Claim, 12 Drawing Sheets(56)
